UNITED STATES PATENT OFFICE.

DAVID W. HAWKSWORTH, OF DETROIT, MICHIGAN, ASSIGNOR TO HUTCHINS CAR ROOFING COMPANY, OF DETROIT, MICHIGAN, A CORPORATION OF MICHIGAN.

OUTSIDE CAR-ROOF.

1,204,841.

Specification of Letters Patent.

Patented Dec. 5, 1916.

Application filed October 13, 1913. Serial No. 794,963.

To all whom it may concern:

Be it known that I, DAVID W. HAWKSWORTH, a citizen of the United States of America, residing at Detroit, in the county of Wayne and State of Michigan, have invented certain new and useful Improvements in Outside Car-Roofs, of which the following is a specification, reference being had therein to the accompanying drawings.

10 The invention relates to car roofs of the type known as outside roofs, in which the board covering is weather-proofed by an overlaid sheathing.

It is the object of the invention to provide 15 greater flexibility or freedom of movement of the metallic sheathing in relation to the board covering and at the same time to secure better weather-proofing qualities than in constructions heretofore used.

20 To this end the invention comprises various features of construction as hereinafter set forth.

In the drawings: Figure 1 is a side elevation of a portion of a car roof to which my 25 improvements are applied; Fig. 2 is an end elevation thereof; Fig. 3 is an enlarged side elevation showing the joint between adjacent sheets; Fig. 4 is a cross section taken on line $w-w$ of Fig. 3; Fig. 5 is a cross section through the ridge; Fig. 6 is a plan view 30 of a portion of the ridge; Fig. 7 is a perspective view of one of the members shown in Fig. 3; and Fig. 8 is a view similar to Fig. 4 taken on a slightly different plane 35 and showing the spiral engaging flanges.

In the present state of the art it is usual 40 to provide car roofs of the type above referred to with attachment means between the weather-proofing sheathing and the roof which will permit a certain degree of independent movement. It is necessary, however, to securely fasten the sheathing to the board roof at distributed points, and experience has demonstrated that these securing 45 points are the places where the sheathing is first broken or torn. With my improved construction I avoid this result by providing a practically continuous securing or holding down means extending around the margin 50 of the sheets, while the required flexibility is secured by a slideable and flexible engagement between individual sheets and the securing means.

In detail, A is the siding, B the fascia and

C the side plate of a car body of usual construction. D is the board roofing and E are the metallic weather-proofing sheets that overlie this boarding. These sheets E are secured to each other so as to permit independent movement to conform to the weaving in the car frame, preferably by providing their adjacent side edges with spiral-shaped flanges F F' telescopically engaging each other. At the ridge the sheets are provided with upstanding flanges G covered by 60 ridge caps H, and which are held down by the saddles I for the running board secured by central bolts J passing between the flanges G of the sheets.

To secure the roofing sheets down at the 70 eaves I provide longitudinally-extending metallic strips K which are rigidly secured to the fascia and plate by nails or other securing means L. The upper edges of these strips have a hooked engagement with the 75 outer edges of the sheets, preferably by forming upon each a spiral flange M, which flanges may be engaged with each other by either a relative rotary or a telescopic movement. The strips K engage the sheets not 80 only at the sides of the car but also across the end thereof and consequently the entire perimeter of the metallic covering is held down upon the car frame.

To avoid cutting down the side clearance 85 of the car, the spiral flanges M are arranged above the fascia and within the plane of the outer face thereof. To this end the strips K are preferably bent to an angular cross section, each being provided with a 90 flange K' which overlies the top of the fascia, the adjacent ends of said flange abutting against each other. The spiral flanges F F' and M of the sheets form weather-proofing joints throughout their extent, but 95 at the corners a space is left by the termination of these flanges which requires further weather-proofing. This is preferably accomplished by an angularly bent strip N, which lies beneath the abutting edges of 100 the strips K and which extends upward from the top of the fascia and also above the roofing board, the inwardly-extending flange N' thereof being of sufficient extent to prevent all danger of leakage. A still 105 further weather-proofing device is provided which consists in a cap member O overlying the joint between the abutting ends of

the strips K and extending beneath the ends of the flanges F and F'. This cap is secured in position without perforation therein by a bolt P, which passes through a vertical aperture in the fascia, and has its head in engagement with a recess in the cap, having an entrance slot from the inner end thereof.

With the construction as described, it will be understood that the metallic sheathing is completely weather-proofed: first, by the engagement of the flanges F and F' of adjacent sheets; second, by the engagement of the flanges M with the corresponding flanges 15 of the strips K; third, by the underlying strip N bridging the joint between the strips K; and fourth, by the caps O overlying these joints. It will also be understood that the separate sheets are free to move independently of each other and of the car body, and are not fixed in position at any point throughout their extent. Thus at the eaves the sheets are free to slide longitudinally upon the strips K and also to move angularly in relation to said strips by the flexing of the engaged spiral flanges. At their side edges the adjacent sheets are free to move independently by a longitudinal sliding movement of the flanges F and F' and 25 angularly by a flexing of said flanges. At the ends of the car there is a similar provision for longitudinal sliding and flexing movement in relation to the strips, while at the ridge the sheets are also free to move 30 limitedly beneath the saddle blocks I.

To limit the movement of the sheets, the cap member O performs the additional function of a stop between the ends of the spiral flanges M. Sufficient clearance is provided 40 between the ends of these flanges and the stop to provide the necessary freedom of the sheets, but a permanent displacement or creeping of the sheets from normal posi-

tion is prevented. Furthermore, the stops are themselves firmly held from displacement by the bolts P so that they cannot be torn off by any ordinary stress to which the roof structure is subjected.

What I claim as my invention is:

1. In an outside car roof, the combination with roof boards and fascia arranged to form a longitudinally-extending rabbet, of roofing sheets supported on said roof boards having spiral eave flanges engaging said rabbet, securing strips having complementary spiral flanges telescopically engaging said eave flanges and attached to said fascia, said strips and flanges being cut away at their ends, stop members arranged in the cut-away portion of said flanges, 50 weather-proofing angle strips overlapping the adjacent ends of said securing strips and beneath said stops, and a bolt for securing said stop to said fascia, engaging a recess in the former and passing through the latter and overlying said angle strips.

2. In an outside car roof, the combination with roof boards and a fascia, of roofing sheets supported upon said roof boards provided with flanges extending over said fascia, securing strips having complementary flanges and attached to said fascia, and combined weather-proofing caps and stops bridging the joints between adjacent securing strips and arranged between the ends of 70 said flanges of adjacent sheets, said combined weather-proofing caps and stops being secured to said fascia by a means extending substantially vertically through said fascia and within said other member.

In testimony whereof I affix my signature in presence of two witnesses.

DAVID W. HAWKSWORTH.
